CURL HOLDING DEVICE

Roy Andrew Smith, New York, N. Y., assignor to
Cosmetics Research, New York, N. Y.

Application February 14, 1951, Serial No. 210,973

1 Claim. (Cl. 132—46)

1

My invention relates to improvements in a hair retaining device and more particularly relates to a device for holding a curl in flattened relation to the head. In forming curls and in setting the hair in the form of waves, it is customary to form a portion of the hair into a relatively tight circular curl or flat "pin curl," which then is set by holding the curl in position and shape overnight or by application of "permanent" waving solutions. Conventional devices for holding the curl in flat position are subject to a number of well-known difficulties and disadvantages which have prompted many proposals to remedy them. Probably the most widely used holding device is the ordinary bobby pin. Since the formation of the curl requires the use of one hand, the bobby pin requires extreme manual dexterity or dangerous use of the teeth in self-application. Care must be exercised in inserting the bobby pin because the flat narrow prongs may dig into the scalp. In addition, its snap spring tension which largely concentrates the pressure at a localized point combined with the narrow overlapping form of its holding prongs tends to kick the curl and mar the appearance of the resulting wave when the curl is brushed out. Indeed the kinking action may actually break individual hairs which is harmful in itself but further aggravated if a wave-setting solution is employed.

Many expedients have been proposed in an effort to remedy these disadvantages and provide a more satisfactory pin curl holding device. Modified variations of the original hair pin have been proposed but have been unsatisfactory because they are difficult to apply, unsatisfactory in firmly retaining all portions of the curl in position, or inclined toward kinking the hair when tensioned for firm holding. More successful have been various hinged and spring-locked clasps and clips. These articles are relatively easy to apply but are uncomfortable for the wearer. The hinged construction increases the cost of manufacture and in use causes discomfort by entangling the hair. Moreover, the hinged construction is associated with broader larger holding members. Smooth-surfaced and flattened for lightness, they tend to slip off the curl entirely. More important, however, is the fact that these articles are very poorly adapted to the use of wave setting solutions since the size and overlapping relation of the clasping members interfere with proper saturation of the hair and with drying.

All of these devices, insofar as I have been able to determine, suffer the additional disadvantage that they depend for holding action upon spring-engaged touching elements or rotating or twisting hinge elements. Accordingly, they cannot be coated as a practical matter with a protective paint or varnish for use with wave-

2

setting solutions. This is a serious disadvantage since lightness, durability and resiliency at the present time require spring metal construction which cannot be used with wave-setting solutions without corrosion, unsightly stains and disturbing discoloration. Plastic construction with a rubber band tensioning element has been proposed for this purpose but bulky, broad and imperforate holding members are required due to the low strength of the plastic material.

The pin curl clip of my invention is peculiarly adapted to holding a curl in flattened relation to the head for wave-setting purposes. The device is easy to apply with one hand and holds the curl securely. An elongated lower holding member guided beneath the curl provides easy leverage against the curve of the head to open the clip to embrace the curl as it is slipped into place without any separate opening act. Light weight resilient construction providing low tension spring action holds the curl firmly without pinching the hair or causing discomfort. Multiple strand combination for the holding members distributes the retaining pressure equally over a great number of points so as to combine security with lightness of clasp. The offset relationship of the upper members to the single looped lower member provides added holding capacities around the inner periphery of the curl which is essential for creation of a neat, uniform wave. The holding members have a minimum overlap and do not touch at any point. Saturation with solution and after drying then are not obstructed. The device can be readily coated as by dipping or tumbling with acid or alkali resistant coatings to provide suitability for use with wave-setting solutions.

My curl holding device is characterized by construction from a light durable resilient material, such as spring steel wire, which is formed into a loop-form base member of flattened ellipsoidal shape having a closed tip. The tip is forwardly and downwardly extended to provide a smooth elongated guide portion. Advantageously, the base member is curved slightly to follow the contour of the head. An upwardly extending arch is provided at the end of the base member opposite the tip from which extend a pair of oppositely disposed loop-form holding members of flattened ellipsoidal shape. By means of the arched construction, the upper members are positioned in spring tensioned relationship over the base member. The upper loop-form members are disposed in offset relationship to the loop-form base member, that is, each loop is positioned astride the corresponding outer portion of the lower loop. The free ends of the offset upper members advantageously are bent slightly upward to form in conjunction with the downwardly extending tip of the base member an opened space to receive the curl.

My invention will be further described in connection with the accompanying drawings in which a typical device and its mode of application are illustrated in simplified form. Figure 1 represents a top plan view of the new type pin curl holding device. Figure 2 represents a side elevation view. Figure 3 illustrates application of the device to a curl and Figure 4 represents the device in position. Figure 5 illustrates the device of my invention in the course of manufacture from flat metal stock instead of wire.

In Figure 1, the essential three-member construction is illustrated by base member 10 and upper offset members 11 and 12. The base member is in loop-form of flattened ellipsoidal shape as indicated by the loop side members 13 and 14. The upper holding members 11 and 12, respectively, are similar, of loop-form construction of flattened ellipsoidal shape with oppositely bowed side members 15, 16, 17 and 18. Advantageously, the device is constructed from a single length of spring steel wire, e. g. of about 0.03 to 0.05 inch thickness. Thin light weight flat stock also may be employed. The material is first bent to form the elongated tip 19 and loop 20 of base member 10. The loop advantageously is pinched together to form the tip 19 which provides a smooth rounded guide portion for inserting the device into the hair. The two free ends of the wire then are arched upwardly to provide a spring tensioning and spacing member 21, better seen in Figure 2. Advantageously, the arches are brazed together at 22 so that both upper members depend from a single joint to provide greater strength for the construction and improved spring tension. The upper members are formed into the loops delineated by side strands 15, 16, 17 and 18. Lateral extensions 23 and 24 provide the required degree of offset between the loops of the upper holding members and the loop 20 of the lower member 10. The ends of the wire completing the loop are brazed tight at 25 and 26. Advantageously, the free ends of the upper members 11 and 12 are pinched together as indicated at 27 and 28.

By reference to Figure 2 it may be seen that the guide portion 19 of base member 10 is bent downwardly and the pinched end portions 27 and 28 are bent slightly upward so as to form an opened mouth or receiving space for the curl. The base member 10 is shaped to the contour of the head and it is important to provide sufficient length in the tip 19 so that when downwardly extended to slide under the curl from any angle the elongated tip will provide sufficient leverage under the curl to easily raise the ends of the upper members 11 and 12 as the clip is slipped into place.

In Figure 5, a device of the general character of that illustrated in Figure 1 is shown as produced by stamping from light weight spring metal flat stock. The various structural and holding members are analogous to those illustrated in Figure 1 and follow the same numbering scheme. The device is illustrated at the manufacturing stage where the spring arch connection at the closed end of the device is to be formed by bending the upper portion comprising holding members 11' and 12' over a rod form or other fixture into spring tensioned relationship with lower guide member 10'.

In application, the curl is formed in the usual way with one hand while the new holding device is held in the other hand. The guide portion 19 of the lower member 10 is inserted below the curl and used as a centering and sliding portion by

feel to bring ends 27 and 28 of upper members 11 and 12 in overriding relationship to the edge of the curl while the curl advantageously is retained with two fingers placed slightly apart. The holding device then may be easily slipped into position as indicated in Figures 3 and 4 without opening the device in any other manner due to the leverage against the head by elongated tip 19 through the curl upon the upper members 11 and 12. The offset relationship between the strands of loop-form base members 11 and 12, with base member 10 centered below the curl, results in evenly distributed pressure on the curl with all portions of the inner periphery which is most inclined to become disengaged in positive engagement.

Hence, my new curl holding device combines in spring tensioned relationship an elongated loop-form base member centered below two offset loop-form upper holding members. The long downwardly curved tip of the central base member in conjunction with the slightly upturned longitudinally extending upper members provides a guiding and gathering action in positioning the clip. No separate opening act is necessary; the clip is merely slipped on regardless of angle of approach to the head as the lever action of the tip takes the tension off the upper members. The likelihood of piercing the curl, leaving free ends, is obviated. The clip need be applied with one hand only. There is no need to resort to the teeth or the nails to open. The rounded end construction eliminates sharp or blade-like "ends" which may cause discomfort or dig into the scalp. The user then can slide the elongated tip comfortably and safely along the scalp to guide the clip into exact position in a manner impossible with conventional pins and clips. The multi-loop form construction with six wire strands over and under the curl provides security of clasp over the greater area of the curl and at all sections of the center. The relative curvature of the members together with the distributed spring action permits a uniform and gentle grip on the curl over the entire holding area, avoiding the kinking and concentrated pressure points of conventional devices. The light weight divided construction covers a minimum amount of hair allowing maximum saturation and drying rate. The simple wire construction and the spread between members permits inexpensive manufacture and ready coating for use with chemically active solutions.

I claim:

55 A device for holding a curl in flattened relation to the head formed of a light durable resilient material and comprising an elongated loop-form base member of flattened ellipsoidal shape curved slightly to follow the contour of the head and having a forwardly and downwardly extended tip, an upwardly extending arch at the end of the base member opposite the tip, a pair of oppositely disposed loop-form holding members of flattened ellipsoidal shape extending from the arched end of the base member in spring tensioned relationship over the base member characterized by offset relationship of each loop to the loop-form base member and having the free ends of the upper members bent slightly upward to form in conjunction with the forwardly and downwardly extending elongated tip of the base an opened receptive space for the curl.

ROY ANDREW SMITH.
